No. 839,677.

PATENTED DEC. 25, 1906.

H. J. TRAH.
AUTOMATIC CUT-OFF.
APPLICATION FILED JAN. 25, 1906.

UNITED STATES PATENT OFFICE.

HENRY J. TRAH, OF LOGANSPORT, INDIANA.

AUTOMATIC CUT-OFF.

No. 839,677.

Specification of Letters Patent.

Patented Dec. 25, 1906.

Application filed January 25, 1906. Serial No. 297,806.

To all whom it may concern:

Be it known that I, HENRY J. TRAH, a citizen of the United States, and a resident of Logansport, in the county of Cass and State 5 of Indiana, have invented a new and Improved Automatic Cut-Off, of which the following is a full, clear, and exact description.

The invention relates to water distribution; and its object is to provide a new and improved automatic cut-off designed for use in house-leaders and the like and arranged to allow the dirty rain-water from the roof of a house to pass to a waste-pipe and then direct the following clear rain-water to a cistern or 15 other reservoir.

The invention relates to novel features and parts and combinations of the same, which will be more fully described hereinafter and then pointed out in the claim.

20 A practical embodiment of the invention is represented in the accompanying drawings, forming a part of this specification, in which similar characters of reference indicate corresponding parts in all the views.

25 Figure 1 is a perspective view of the improvement as applied. Fig. 2 is an enlarged sectional side elevation of the same, and Fig. 3 is a sectional plan view of the same on the line 3 3 of Fig. 2.

30 The leader A on the side of a house is connected at its upper end with the usual gutter B, receiving the rain-water from the roof C of the house, and the lower end of the leader A forms an inlet D for pipes E and F, of which

35 the pipe E connects with a waste-pipe, while the pipe F leads to a cistern or other reservoir used for storing clear rain-water. Normally the inlet D is connected with the pipe E by a gate G, closing the connection between the

40 inlet D and the pipe F. This gate G is hung at its sides on trunnions H and H', of which the trunnion H is secured to the corresponding side of the gate G and is journaled in the pipe E, and on the outer end of this trunnion

45 H is secured a weighted arm I for holding the gate G in the normal position shown in Fig. 2 and above mentioned. The gate G is provided at or near its middle with an aperture G', preferably covered by a screen G², and

50 through the said aperture G' passes a portion of the dirty rain-water flowing at the beginning of a rainfall from the roof C into the gutter B and from the latter by way of the leader A to the pipe E. Now this water

55 after passing through the aperture G' flows into a receptacle J, connected at its upper

end by links K with the sides of the gate G and points to one side of the trunnions H and H', and when this receptacle J is about filled with water then it overbalances the weighted arm I and swings the gate G into a reverse position to cut off the inlet D from the pipe E and to connect the inlet D with the pipe F. Thus the following clear rain-water flows to the pipe F and to the cistern or other reservoir in 65 which the rain-water is to be stored.

The upper end of the receptacle J is preferably provided with a screen J', which, like the screen G², previously mentioned, serves to prevent dirt and other impurities from passing 70 into the receptacle J to the pipe F. The bottom of the receptacle J is provided with a drain-opening J², by which the water may gradually drain from the receptacle J into a chamber L, having an inclined bottom opening at the sides, at L', into the pipe F. Now it is evident that after the rainfall the flow of the water into the cistern or reservoir ceases and the water gradually drains out of the receptacle J, so that the weighted arm I finally 80 overbalances the receptacle J and swings the gate G back to its normal position, (shown in Fig. 2,) thereby resetting the gate, so that on the next rainfall the dirty rain-water is again directed to the pipe E, and the gate G is only 85 shifted after the receptacle J has filled with water and overbalances the weighted arm I, as above explained, so that the subsequent clear water passes by way of the pipe F to the cistern or other reservoir.

90 The automatic cut-off shown and described is very simple and durable in construction, and as the water contained in the receptacle J drains out of the same after the rainfall is over the several parts are not liable to freeze 95 up and become immovable in cold weather.

It is understood that as long as water flows down the leader A to the pipe F, as previously explained, the receptacle J is kept filled with water to overbalance the weighted arm I; 100 but after the flow of water ceases the receptacle J becomes lighter by the water draining out of the same, so that the weighted arm I finally overbalances the receptacle J and swings the gate G back to its normal position. 105

Having thus described my invention, I claim as new and desire to secure by Letters Patent—

An automatic cut-off for house-leaders, comprising an inlet, a waste connection and a 110 reservoir connection, a chamber between the waste connection and the reservoir connec-

tion, and below the junction thereof, said chamber having an inclined floor leading into the reservoir connection, a swinging gate at the junction of the connections and the inlet, and 5 normally closing the reservoir connection, said gate having an opening through the center thereof and being provided with trunnions whereby to support the gate, a weight connected with one of said trunnions for retaining the gate in its normal position, links connected with the gate at one side of the trunnions, a receptacle connected with the links and arranged below the opening in the gate to receive water therethrough whereby to coun-

terbalance the weight and open the gate, said receptacle moving in the chamber between the waste connection and the reservoir connection, and being provided with openings in the bottom thereof whereby to drain the water therefrom. 15

20 In testimony whereof I have signed my name to this specification in the presence of two subscribing witnesses.

HENRY J. TRAH.
